UNITED STATES PATENT OFFICE.

CHARLES B. PUTNAM, OF MARION, IOWA.

WINDMILL-TOWER.

SPECIFICATION forming part of Letters Patent No. 357,290, dated February 8, 1887.

Application filed November 6, 1886. Serial No. 218,148. (No model.)

To all whom it may concern:

Be it known that I, CHARLES B. PUTNAM, a citizen of the United States, and a resident of Marion, in the State of Iowa, have invented 5 a new and useful Improvement in Windmill-Towers, of which the following is a specification.

This invention relates to that class of towers, sometimes termed "skeleton towers," 10 which are built mainly of "gas-pipe" or iron tubing.

It consists in certain novel combinations of parts and in peculiarly-constructed "corner-irons," as hereinafter set forth and claimed, 15 and its distinctive objects are, first, to secure a strong and rigid tower capable of being easily and quickly erected without the customary numerous screw-joints, which involve the use of pipe-tongs by skilled artisans; secondly, to 20 facilitate bracing such structures without obstructing the interior; thirdly, to so brace such structures with a single set of turn-buckles and two sets of brace-rods to three sets of horizontal cross-bars, or "struts," as 25 they are hereinafter termed; fourthly, to attach such horizontal struts to uncut corner-posts by interchangeable corner-irons; fifthly, to facilitate clamping such corner-irons upon 30 said corner-posts; and, sixthly, to securely support the customary platform or gallery immediately below the top of the tower by simple and interchangeable collars.

A sheet of drawings accompanies this specification as part thereof.

35 Figure 1 of these drawings is an elevation of a windmill-tower illustrating this invention. Fig. 2 is a plan view of its upper portion. Fig. 3 represents a section on the line 3 3, Fig. 1, segregating the braces of one side 40 of the tower. Fig. 4 is a perspective view of one of the corner-irons on a larger scale. Fig. 5 represents a horizontal section through a corner-iron in the tower on the same scale; and Figs. 6 and 7 are perspective views, 45 respectively, of a turn-buckle and a gallery-supporting collar, on said larger scale.

Like letters of reference indicate corresponding parts in the several figures.

My improved tower comprises corner-posts 50 P of iron tubing, which may be, and preferably are, "uncut"—that is to say, each of a single

length of the tubing and free from drill-holes and the like. These corner-posts are preferably four in number, making the tower "square," as represented; but the tower may 55 have only three, or more than four, sides, if preferred, without affecting the principle of construction herein set forth. Each post is provided with corner-irons I, one of which is shown detached by Fig. 4, and a gallery-supporting collar, C, Fig. 7, which are clamped thereon at proper heights by set-screws s, and "flange-unions" F U, are made fast in any 60 approved way, as by screw-joints, on the respective extremities of each post. Each side 65 of the tower comprises, furthermore, two or more horizontal struts, S S' S'', of tubing of smaller size, preferably three, of graduated lengths, four or more brace-rods, R R', and two 70 or more turn-buckles, T, one of which is shown 75 detached by Fig. 6. Anchors A, of wood or stone, a gallery, B, and a cap, C', consisting of the base or turn-table of the windmill, with screw-bolts b, uniting said flange unions F U with said anchors A and with said cap C', respectively, complete the structure as regards 80 the present invention. Said corner-irons I, turn-buckles T, collars C, and flange-unions F U may be, and are preferably, iron castings, and the rods, screws, and bolts of suitable 85 wrought-iron. Each of said corner-irons I has, as shown in Figs. 4 and 5, a tubular body, z, fitted internally to that diameter of tubing of which the corner-posts P are made, and a pair of lateral sockets, x, fitted to that diameter of tubing of which the struts S S' S'' are 90 formed, with a web, w, connecting the shells of the latter, and provided with a pair of drill-holes, v, fitted to the iron of which the rods R are made, and parallel to said body z, which 95 is at an angle, relatively to the vertical axis of the tower, determined by the convergence of the corner-posts. A pair of drilled and tapped holes, u, in said body z receive the said set-screws s of the corner-iron, and are substantially in line, respectively, with the axes of said sockets x, but at right angles to that of the body z. Each of said rods R, as 100 shown in Figs. 3 and 5, is inserted through one of said holes v in one of the corner-irons I, and each of said rods R through two diagonally-opposite corner-irons; each has a head,

h, at one end, and its other end, *s'*, is screw-threaded. These ends *s'* are connected by said turn-buckles *T*, each of which has, as shown in Figs. 3 and 6, an internal screw-thread, *t'*, in each end, respectively, "right" and "left," and a central lug, *t*, by which to turn it. Each of said collars *C* has, as shown in Figs. 2 and 7, a pair of radial spurs, *r*, and between them a radial drilled and tapped hole, which is fitted 10 with its said set-screw *s*. Each of said flange-unions *F U* has, as indicated in Figs. 1 and 2, a central socket fitted, as to angle and internal diameter, to either of the corner-posts, and a horizontal body or "flange," the latter provided with a pair of vertical bolt-holes fitted 15 to said bolts *b*. The details of these flange-unions form no part of my present invention, and these and other mechanical details not particularly specified may be of any approved 20 character.

The parts having been assembled, as represented by Figs. 1, 2, 3, and 5, and loosely united, with the tower erect in the position which it is to occupy, the lower flange-unions, 25 *F*, may first be made fast to the anchors *A* by their bolts *b*. The corner-irons *I* may next be finally adjusted so as to render the successive sets of struts *S S² S³* horizontal at the heights for which they are respectively cut, 30 and then tightened upon the posts by their set-screws *s*. The rods *R R²* may next be put in tension by means of the turn-buckles *T*, so as to fasten the struts and render the entire structure rigid and secure.

35 As seen in Figs. 1, 3, and 5, the rods *R R²*, which brace each side of the tower, hang in an inner plane substantially parallel with the plane of its pair of posts *P* and that of its struts *S S² S³*, and close to the latter, so as to 40 leave the interior of the tower wholly unobstructed as regards brace-rods; and, as seen in Figs. 1 and 3, a single set of turn-buckles, *T*, in a single horizontal plane, serves, with two sets of brace-rods, *R R²*, to tighten three sets 45 of struts, *S S² S³*.

Owing to the construction of said corner-irons *I*, (best seen in Figs. 4 and 5,) they are interchangeable throughout the structure, and it may be throughout all towers of a given 50 plan, and they provide for strongly attaching brace-rods and struts to uncut corner-posts, so that the former obviate screw-joints between the corner-irons and struts. The peculiar disposition of the pair of set-screws of 55 each corner-iron utilizes the resistance afforded by its respective companion posts and the interposed struts in tightening the iron upon a post. (See Figs. 1 and 3.) Said interchangeable collars *C*, fastened upon the un- 60 cut corner-posts by their set-screws *s*, serve not only to support the gallery *B* from beneath, but by their radial spurs *r* tie the same to the corner-posts. (See Fig. 2.) Said flange-

unions *F U* and their bolts *b*, in connection with the uncut corner-posts *P*, strongly and 65 directly connect the windmill turn-table to the foundations of the tower. (See Fig. 1.)

Having thus described my said improvement in windmill-towers, I claim as my invention and desire to patent under this specification—

1. The combination, substantially as herein specified, of uncut inclined corner-posts and horizontal struts of iron tubing, corner-irons having tubular bodies fitted to said posts, lateral sockets fitted to the ends of said struts and perforated webs connecting said sockets, brace-rods passing through said webs, and turn-buckles connecting said rods, for the purpose set forth.

2. The combination, substantially as herein specified, of corner-posts, horizontal struts, corner-irons having bodies fitted to said posts, lateral sockets fitted to the ends of said struts and perforated webs connecting said sockets, 85 and a system of brace-rods and turn-buckles, the former passing through said webs in inner planes substantially parallel to those of the respective pairs of posts, for the purpose set forth.

3. The combination, substantially as herein specified, of three or more corner-posts, three sets of corner-irons and horizontal struts, the former having bodies fitted to said posts, sockets fitted to the ends of said struts and perforated webs connecting said sockets, two sets of brace-rods passing through said webs, each rod having a head at one end, and a single series of turn-buckles connecting said rods in pairs, for the purpose set forth.

4. The within-described interchangeable corner-irons, each constructed with a tubular body, a pair of lateral sockets, and a perforated web connecting said sockets, substantially as shown, for the purpose set forth.

5. The combination, with uncut corner-posts and interposed struts, of corner-irons having lateral sockets fitted to the ends of said struts, and tubular bodies fitted to said posts, said bodies being also drilled and tapped and provided with set-screws substantially in line with the respective lateral sockets, substantially as herein specified, for the purpose set forth.

6. The combination, with uncut corner-posts, of the within-described collars, each having a pair of radial lugs and a screw-tapped radial hole provided with a set-screw, and a gallery surrounding said posts and supported upon said collars, substantially as herein specified, for the purpose set forth.
